(57) **CLAIM**

The ornamental design for a baffle plate, as shown and described.

DESCRIPTION

FIG. 1 is a front view of a baffle plate showing our new design. FIG. 2 is a rear view of the baffle plate of FIG. 1.

FIG. 3 is a top plan view of the baffle plate of FIG. 1.

FIG. 4 is a bottom plan view of the baffle plate of FIG. 1.

FIG. 5 is a right side view of the baffle plate of FIG. 1.

FIG. 6 is a left view of the baffle plate of FIG. 1.

FIG. 7 is a front perspective view of the baffle plate of FIG. 1.

FIG. 8 is a rear perspective view of the baffle plate of FIG. 1; and,

FIG. 9 is a front perspective view of the baffle plate of FIG. 1 shown in a used condition with a plasma processing device shown in broken lines.

The features shown in broken lines depict environmental subject matter only and form no part of the claimed design.

1 Claim, 4 Drawing Sheets
